UNITED STATES PATENT OFFICE

CHARLES T. HOFFMAN, OF WASHINGTON, DISTRICT OF COLUMBIA

RAIL ANCHOR

Application filed January 9, 1930. Serial No. 419,599.

This invention relates to devices for preventing the longitudinal creep of railroad rails, such devices being known to the art as anti-creepers, rail anchors, creep checks, or rail stays.

A general object of the invention is to provide a device that will be simple in construction, relatively cheap to manufacture, light in weight, strong, and capable of retaining a firm and reliable hold on the rail while at the same time being adapted for production by well known and usual manufacturing methods.

A primary object of the invention is to provide a construction whose grip on the rail will not be affected by the vibration or movement of the rail, temporarily, in a direction opposite to that in which the rail tends to creep or by any other cause tending to displace or loosen the grip of the anti-creeper on the rails engaged thereby. In that connection the invention also contemplates a rail anchor which will provide effectually against rail creeping in either direction and which is operative essentially by the application of the weight of the moving track load although held in its original gripping position by its application to the rail so that not only an initial strong rail gripping action is secured but under normal operating conditions when the rolling load is applied to the rail a greater grip will be obtained.

A further object is to provide a combined rail anchor and tie plate so that the installation of both the tie plate and anti-creeper or rail anchor may be simultaneous thus requiring no substantial labor in its installation in addition to that necessary in the installation of an ordinary tie plate.

A still further object of the invention is to provide a rail anchor of the type set forth which possesses sufficient resiliency to prevent tie and ballast shock, and, because of the inherent resiliency of the anti-creeper force applied to the rail, is adapted to effect the primary purpose without uneven tie end drag, gauge disturbance, side rail wrenching, and which will also distribute the anti-creep-

ing force evenly to both rails under fast moving track loads.

A preferred and practical embodiment of the invention is shown in the accompanying drawings in which:

Figure 1 is a side elevation of the improved rail anchor and anti-creeper applied in position between a rail base and a tie. 55

Figure 2 is an end elevation of the combined tie plate and rail anchor showing the rail anchor more in detail. 60

Figure 3 is a view similar to Figure 1 showing a tie plate with the rail anchoring means applied to both ends thereof.

Figure 4 is a side elevation illustrating a modified form of rail anchoring tie plate. 65

Figure 5 is an end elevation of the rail anchoring portion of the plate shown in Figure 4.

Figures 6 and 7 are respectively detail cross sectional views, illustrating different shapes that may be given to the rail base engaging portion of the rail anchor. 70

Figure 8 is a side elevation illustrating the use of the invention in connection with the cambered plate. 75

Figure 9 is a perspective view of a further modification illustrating the application of the invention to a tie plate having gauge maintaining shoulders. 80

Figure 10 is a detail elevation of a further modified form of rail gripping means.

Similar reference characters designate corresponding parts throughout the several figures of the drawings. 85

The essential function of a rail anchor or anti-creeper is to resist rail creeping or the intermittent or sliding movement of the rails in track under moving rail loads. Rails creep from two principal causes; first, the application of brakes to moving car wheels; and second, due to the undulating or wave motion of the track caused by the depression of the rails under the intermittent rolling loads of the wheels of passing trains. Other factors tending to contribute to rails creeping are insufficient expansion allowance, loose spikes and bolts, long spaces between ties, yielding foundations, and insufficient roadway drainage. 90

A very desirable factor in track construction is to limit the number of separate parts per section of track to a minimum, and the present invention fulfills this requirement both as to installation and maintenance. Many anti-creepers or rail anchors in extensive use contain as many as four members at the junction of the rail and tie, to wit, the tie plate and an associated anti-creeper, the latter including from one to three separate members. Accordingly in the present invention, it is proposed to provide a rail anchor or anti-creeper integral with the tie plate, and which, while remaining in one roller member, is adapted to be operative in both directions of rolling track load, and whose effectiveness does not depend upon the tightness, strength or support of the associated rail spikes. Therefore, the present invention clearly possesses the desired advantages necessary to the maintenance of proper track conditions.

Also the present invention provides for the anti-creeping reactive force by independent anchorage on either or both sides of the tie at the junction of the rail and tie and does not depend for its operativeness upon the actual creeping of the rail as is true with the majority of anti-creepers in use.

Referring first to Figure 1 of the drawings, it will be observed that the tie plate portion is designated generally as 1, and in the illustration shown has the rail anchoring means R at one end thereof. The combined anchor and tie plate are preferably rolled from spring steel and the rail anchoring means then cut to shape and bent or folded to provide the integral folded portion including the depending tie abutting leg 2 and the upturned leg or member 3. This latter member preferably extends above the top line or surface of the tie plate 1 and has its central portion cut away to permit of the rail seating between a pair of upstanding rail gripping members 4. These members are forced into gripping engagement with the side edges 5 of the rail base B by reason of the weight and load of the rail acting upon the unsupported ends of the inwardly projecting lever portions 6 formed integrally from the web of the upstanding member. That is to say, the member 3 of the rail anchor R is so formed as to provide the upstanding side gripping members 4 which are pulled inwardly when the rail seats on the upper surfaces 7 of the inwardly projecting lever portions 6 which also serve to bind against and grip the base of the rail. Thus, a two-fold rail grip is secured, one at the side edges of the rail base and another directly on the bottom face of the rail. It will, of course, be understood that the upper surfaces 7 of the web members 6 normally have a projection above the upper rail seating surface of the tie plate portion 1 so that as the rail is placed in position on the tie plate it will first engage the upper edges 7 of the

members 6—6 and, as the rail moves toward its seating position on the plate between the members 4—4, the latter will be drawn inwardly to grip the side edges of the rail base while, at the same time, the base will be gripped by the members 6—6.

The upturned member 3 may be formed in various ways to secure the effect pointed out. According to Figures 1 and 2 the inturned web portions 6—6 may be formed into levers by cutting away the metal of the member vertically as indicated at 8 and horizontally as indicated at 9, thereby to produce a comparatively small opening which will effectually resist the entrance of ballast or other matter which might prevent the free downward movement of the members 6—6 to cause the bending inward of the members 4—4 as indicated by the dotted lines in Figure 2. The upper surfaces of the members 6 are preferably inclined toward the base edges of the rail so that a progressively increased bearing engagement is effected between the same and the base of the rail. This is done so that not only an effective initial grip will be secured, but as the rolling load approaches the zone of the rail anchor and the rail deflects under such load, the members 6 will be thrust further downwardly and not only securely grip the base of the rail but also the members 4—4 will be moved inwardly to more tightly grip the side edges of the rail base.

Figures 1 and 2 of the drawing illustrate an embodiment of the invention wherein the rail anchor and tie plate are combined and the rail gripping means is integral with one end of the tie plate.

Figure 3 of the drawings, however, illustrates the tie surface engaging portion 1 or tie plate having the integral rail anchors R and R' at each end thereof. The construction of the rail gripping means of the rail anchors R and R' may be the same as that shown in Figure 2, or they may be modified as shown in Figures 4 and 9 of the drawings. However, the purpose of the construction shown in Figure 3 is to provide a double rail anchor which will provide a double grip on the rail and is particularly adaptable to rails on which traffic runs in both or opposite directions.

Another object of this type of rail anchor is that it assists in preserving the tie, and although preferably held to the tie by the aid of the usual spikes S this type of anchor may be installed at locations where spikes become a secondary fastening element since this type straddles the tie and provides a self-seating and self-locking tie engagement.

Figure 4 of the drawings illustrates a type of anchor R² which includes the rail gripping members 4^b for engaging the side edges of the rail base B, the same being integrally connected with the lever elements 6^b whose upper edges 7^b have the initial elevated set-

ting shown by the dotted lines in Figure 4 so that when the rail seats on the tie plate, it will initially depress the lever elements 6^b and pull the rail gripping members 4^b inwardly from the dotted line position to the full line position shown in this figure. In the type of anchor shown in Figure 4, the levers 6^b are formed from the web of the upturned member 3^b by making the substantially triangular opening 10. This arrangement locates the fulcrum point of the metal in the web lower and further toward the side edges of the body 3^b and is useful to illustrate the range of modification which may be resorted to in the formation and shape of the levers 6^b.

As will be observed from Figure 5 of the drawings, the rail anchor R^a shown in Figure 4 includes the depending leg 2^b and the upstanding leg 3^b and, if desired, the upstanding leg 3^b may be left initially out of contact with the depending leg 2^b. When the rail creeps in the direction of the arrow in Figure 5, it will be apparent that the leg 3^b may have a tendency to move in the arc of a circle, and in doing so the deflection of the rail due to the wheel load approaching the tie T will cause a greater deflection of the levers 6^b due to the tendency of the rail to carry the rail anchor through the arc of a circle having as its radius the leg 3^b. That is to say, any tendency of the rail to creep will meet with greater resistance if the creeping movement tends to force the leg 3^b toward the member 2^b.

Figure 8 of the drawings illustrates the application of the invention to a cambered type of tie plate. In this embodiment the tie plate portion 1^a is shown in its normal position in full lines and has the rail anchor R at one end thereof. The position of the plate under load is shown in dotted lines. Clearly this form of tie plate gives greater efficiency to the rail anchor R since when the cambered tie plate portion 1^a is depressed the rail base engaging portions of the rail anchors will have a tendency to lift and press tighter against the base of the rail and thus draw the rail gripping elements 4 or their equivalents into tighter gripping engagement with the sides of the rail base.

Figure 9 of the drawings illustrates a tie plate portion 1^b having the opposite gauge maintaining ribs 11, thus showing the adaptation of the invention to a combined rail anchor and tie plate wherein the plate as well as the anchor may carry the rib element throughout its formation. In this form, the rail anchor is designated as R^a and includes the depending leg 2^a and the upstanding member 3^a, the latter being cut away to provide the upstanding rail gripping elements 4^a and also being cut away or slotted as indicated at 12, to provide the levers 6^a having the relatively flat rail base engaging portions

7^a. As indicated, in other forms of the invention, the lever elements 6^a are provided adjacent the rail base engaging elements 7^a with the clearance portions 6^a, it being understood, of course, that the rail base engaging portions 7^a have an initial projection or disposition above the normal plane of the rail seating surface of the tie plate portion 1^b. This clearance insures the application of the loading force to the outer end of the levers 6 or their equivalent, thus insuring proper functioning of the rail gripping elements 4 or their equivalents under all conditions of use.

Figures 6 and 7 illustrate alternative formations for the top edges 7 of the levers 6. That is to say these members may have their top edge flat as shown in Figs. 1, 2, 3, 4, 5, 8 and 9 or they may be pointed as shown in Fig. 6 or rounded as shown in Fig. 7. These illustrations show the range of modification that may be employed in connection with the rail base engaging edges of the levers when desired.

Figure 10 shows a modification of the upwardly disposed member 3^a wherein the lever element 6^a is in one piece. That is to say, the lever 6^a is formed by slotting the web of the member 3^a as indicated at 11 which provides the necessary clearance for the depression of the lever 6^a to pull the rail flange gripping elements 4^a against the base flanges as in the other forms of the invention. This arrangement may provide for more conveniently cutting and folding the member 3^a under some conditions of manufacture. The part 7^a bears against the bottom of the rail and has an initial setting above the plane of the rail seating surface.

I claim:

1. A rail anchor including a portion adapted to lie between the rail and the tie and a tie abutting portion having rail gripping means.
2. A rail anchor including a portion adapted to be anchored to the tie and a tie abutting portion having integral rail gripping means.
3. A rail anchor including a portion adapted to be anchored to the tie, a tie abutting portion having resilient rail gripping means rendered effective when the rail seats on the portion lying between the rail and the tie.
4. A rail anchor including a portion adapted to be anchored to the tie, a tie abutting portion having resilient rail gripping means rendered effective when the rail seats on the portion lying between the rail and the tie, said resilient rail gripping means being located beyond the limits of the tie to be increasingly effective as the rolling wheel load passes thereover.
5. A rail anchor including a tie plate portion and a rail gripping portion formed integral therewith and disposed at substantially right angles thereto to provide a tie abutting portion.

6. A rail anchor including a tie plate portion and a rail gripping portion formed integral therewith and disposed at substantially right angles thereto to provide a tie abutting portion, said rail gripping portion including a folded bar comprising a down-turned member and upturned member, and means on the upturned member for gripping the rail.
- 10 7. A rail anchor including a tie plate portion and a rail gripping portion formed integral therewith and disposed at substantially right angles thereto to provide a tie abutting portion, said rail gripping portion including a folded bar comprising a down-turned member and an upturned member, said upturned member being cut away to provide upstanding inwardly deflectable side members for gripping the sides of the rail base and also cut away to provide rail base engaging members integrally connected with the upstanding side members whereby the loading of the said rail base engaging members pulls the side members inwardly.
- 15 8. A rail anchor including a tie surface engaging and a tie side abutting portion, said tie abutting portion including a relatively fixed tie engaging member and relatively free rail engaging members having a plurality of rail gripping parts rendered progressively of increasing efficiency under increased loading conditions.
- 20 9. A rail anchor including a tie surface engaging and a tie side abutting portion, said tie abutting portion including a relatively fixed tie engaging member, said rail engaging member being cut away to provide a rail receiving recess and upstanding rail flange engaging members at the sides thereof, and also cut away to provide resilient rail base engaging members having an initial projection above the top of the tie surface engaging portion and integrally connected with the upstanding rail flange engaging members whereby to act as levers under load to increase the grip of the said rail flange engaging members.
- 25 10. A combined rail anchor and tie plate having integral resilient rail gripping means at one end, said rail gripping means being increasingly effective under increased load.
- 30 11. A combined rail anchor and tie plate having an integral substantially U-shaped portion overhanging the edge of the tie and resilient rail gripping means on the free leg of said U-shaped portion.
- 35 12. A rail anchor comprising a part secured to the tie, and rail gripping means including a lever actuated by rail loads to render the rail gripping means effective.
- 40 13. A rail anchor comprising a part secured to the tie and integral rail gripping means including an integral lever having an initial setting above the plane of the rail base and adapted to be engaged thereby to render said rail gripping means effective.
- 45 14. A rail anchor including means for gripping the base flange of the rail, and means engaging with and actuated by the bottom of the rail for rendering said means for gripping the rail effective.
- 50 15. A rail anchor including means for engaging the base flange of the rail and means integral therewith adapted to engage and be actuated by the base of the rail to render said first named means effective.
- 55 16. A rail anchor including a tie plate and means integral therewith for engaging the base flange of the rail; and means integral with said last named means for engaging the base of the rail to then render the means for engaging the base flange of the rail effective.
- 60 17. A rail anchor including a member for engaging the base flange of a rail and a member integral therewith for engaging the base of the rail, said member being fulcrumed at a point below the rail base whereby rail loads imposed on the last named member will cause the first named member to impinge on the rail flange.
- 65 18. A rail anchor including a metallic part supported at one side of the tie, a rail flange gripping member and an offset rail base engaging member formed from said metallic part and said members having a fulcrum located in said metallic part.
- 70 19. A combined rail anchor and tie plate having integral rail gripping means at one end, said means including a part for engaging the base flange of the rail, and means integral therewith adapted to engage and be actuated by the base of the rail to render effective said part engaging the base of the rail.
- 75 20. A rail anchor including a tie abutting portion having means for holding the same in fixed relation to the rail base and also having integral rail gripping means rendered effective by the weight of the rail and wheel loads imposed thereon.
- 80 21. A rail anchor comprising a relatively fixed supporting and tie abutting part and rail gripping means including a lever actuated by rail loads to render the rail gripping means effective.
- 85 22. A rail anchor comprising a relatively fixed tie abutting member and rail gripping means integral therewith, said means including a lever having a part initially set above the plane of the rail base and adapted to be engaged thereby to render said rail gripping means effective.
- 90 23. A rail anchor of substantially U-shaped formation having means on one arm of said U-shaped portion for supporting the same in fixed relation to the base of the rail, and having integral resilient rail gripping means on the other arm thereof.

24. A rail anchor including a metallic body doubled upon itself to form opposite leg portions, means on one of said leg portions for holding the body in relatively fixed relation to the rail and means on the other leg of the body for yieldingly gripping the rail.

In testimony whereof I affix my signature.
CHARLES T. HOFFMAN.
